ELECTRICALLY ACTUATED VARIABLE
ELECTRIC TIME SWITCHRobert P. Mohn, Teaneck, N. J., assignor to
Chester R. Mohn, Teaneck, N. J.

Application April 14, 1950, Serial No. 155,951

6 Claims. (Cl. 200—122)

1

This invention relates to a novel construction of electrically actuated time switch for controlling an electric circuit in which the switch is interposed so that electrically energized devices, connected to said circuit may be de-energized after different elapsed periods of time ranging up to or exceeding thirty-two hours.

An important object of the present invention is to provide such a time switch which is capable of being utilized with either direct current or alternating current and which is of extremely simple construction yet very efficient in accomplishing its intended result.

A further object of the invention is to provide an electric time switch having a delayed action which is accomplished through a novel snap action movement to accomplish a positive and instantaneous interrupting of the electric circuit at the prescribed time and which includes a secondary make and break switch or circuit means which is likewise actuated by a snap action movement for accurately accomplishing the timing and operation of the device.

Various other objects and advantages of the invention will hereinafter become more fully apparent from the following description of the drawings, illustrating a presently preferred embodiment thereof, and wherein:

Figure 1 is a side elevational view, partly in vertical section illustrating one preferred construction of the time switch;

Figure 2 is a plan view thereof;

Figure 3 is a horizontal sectional view taken substantially along a plane as indicated by the line 3—3 of Figure 1;

Figure 4 is a cross sectional view taken substantially along a plane as indicated by the line 4—4 of Figure 1;

Figure 5 is a longitudinal sectional view taken substantially along a plane as indicated by the line 5—5 of Figure 1;

Figure 6 is a longitudinal sectional view, partially diagrammatic, taken substantially along a plane as indicated by the line 6—6 of Figure 1, and

Figure 7 is a diagrammatic view illustrating the electric circuit with which the switch is associated.

Referring more specifically to the drawings, the variable time switch comprising the invention is designated generally 10 and includes a frame, designated generally 11 which is best illustrated in Figure 3 and which comprises a plate having laterally offset substantially parallel longitudinally extending portions 12 and 13 and transversely extending portions 14 and 15. The portion 14 constitutes an intermediate part of the plate and extends between the adjacent ends of the longitudinally extending longitudinally spaced portions 12 and 13. The portions 13 and 15, which are disposed at right angles to one another, constitute the end portions of the frame

2

11. As seen in Figure 1, the end portion 13 has a part extending downwardly below the level of the bottom edge of the transverse portion 14 and a plurality of blocks 16 of insulating material are secured to said depending part of the frame portion 13 by fastenings 17. Another group of blocks 18 of insulating material are secured to the opposite sides of the frame portion 13 by additional fastenings 19 and above the level of the blocks 16.

As best illustrated in Figure 5, a bimetallic strip 20 has one end clamped between two of the blocks 16 by said fastenings 17 and its opposite free end extends longitudinally of the switch 10, passing beneath the frame portion 14 and to beyond the frame portion 15. A strip 21 of spring metal has one end clamped between two of the blocks 16, in laterally spaced relationship to the bimetallic strip 20 and extends therefrom to a point between the frame portions 14 and 15. Two strips 22 and 23 of spring metal are clamped between two of the blocks 16 and likewise extend toward but terminate short of the frame portion 15. The strip 23 is longer than the strip 22 and said strip 22 is in turn longer than the strip 21 and is disposed between the strips 21 and 23. The strip 21 is in turn disposed between the bimetallic element 20 and the strip 22. A rigid bar 24 is clamped between one of the blocks 16 and the frame portion 13 and likewise extends toward the frame part 15 but is substantially shorter than the strips 21, 22 and 23. A screw 25 extends threadedly through the bar 24 and has a cap 26 of electrical insulating material which extends through a slot 27 of the strip 23 and bears against the strip 22, as seen in Figures 1 and 5. The strips 21 and 22 are provided on their adjacent sides and near their free ends with contact points 28 and 29, respectively. A horseshoe-shaped spring 30 has one end engaging an opening 31 of the spring strip 23, between the free end of said strip and its slot 27 and the opposite end of the spring 30 extends through the slot 27 and engages an opening 45 32 in the spring strip 22 and which is located near the free end thereof. The major portion of the spring 30 is disposed on the outer side of the strip 23 or away from the strip 22 and said spring 30 is provided with reversed bends 33, adjacent its ends and which bends engage the openings 31 and 32. A relatively long pin 34 extends slidably through the bimetallic element 20, near its free end, and has a shank end which is secured to the spring strip 23 adjacent the free end thereof and beyond the spring 30. The pin 34 is provided with a head 35 which is disposed on the opposite side of the bimetallic element 20 to the side thereof which is located adjacent strip 21. A spacing sleeve 36 is disposed on the pin 34 between the bimetallic element 20 and strip 23. The shank of the pin 34 is of sufficient length so that the head 35 is spaced suf-

ficiently from the sleeve 36 to allow the bimetallic element 20, which loosely engages the pin 34, to swing relatively to the pin head 35 and sleeve 36 between its full and dotted line positions of Figure 5 without displacing the pin 34 laterally of the frame 11. The strips 21, 22 and 23 are formed of electrical conducting material.

Referring particularly to Figures 3 and 6, a substantially rigid bar 37 has one end clamped between the frame portion 13 and the adjacent block 18 and extends therefrom toward the frame end 15 and terminates short thereof. The opposite end of the bar 37 is turned back to provide a loop 38 in which is anchored the ends of a pin 39. The loop 38 and adjacent portion of the bar 37 is provided with a longitudinal slot 40, as seen in Figure 4, to accommodate a cam, designated generally 41 which is swingably mounted on the pin 39. The cam 41 is notched to provide two oppositely facing abutment surfaces 42 and 43 which are disposed at oblique angles to one another. The cam 41 is formed of electrical insulating material. The cam 41 is provided with an outer surface 44 which is located more remote to the pivot 39 than another surface 45 thereof, for a purpose which will hereinafter become apparent. Two additional spring strips of electrical conducting material, designated 46 and 47 are clamped at corresponding ends thereof between certain of the blocks 18 and extend to beyond the cam 41 and are disposed outwardly of the bar 37. The strip 48 is disposed between the strip 47 and bar 37 and said strips 46 and 47 are provided at their free ends and on their adjacent sides with contact points 48 and 49, respectively, which are normally disposed out of engagement when the spring strips 46 and 47 are in normal parallel relationship, as seen in Figure 3.

The frame portions 14 and 15 are provided with aligned bearings 50 and 51, respectively, for journaling spaced portions of a shaft 52. The shaft 52, between the bearings 50 and 51 is provided with a right hand threaded portion 53 which is engaged by a nut 54. A plate 55 is secured to one side of the nut 54, in any suitable manner as by welding, and is provided with an arm or extension 56 which extends upwardly and which slidably engages in a longitudinally extending slot 57 of a cover plate 58 which is secured to the upper edge of the frame 11 and which is preferably provided with apertured ears at its ends as seen at 59, whereby the switch 10 may be mounted on a suitable supporting surface with the cover plate 58 in either a horizontal or vertical position and with the parts, previously described, extending into a recess or opening of such surface, not shown. It will be readily apparent that the extension arm 56 prevents the plate 55 and nut 54 from turning on the threaded shaft portion 53 so that when the shaft 52 is revolved, the plate and nut will move longitudinally thereof within the limits as provided by the slot 57. The shaft 52 is provided with a restricted threaded terminal 60 to receive a nut 61 which bears against the outer side of the frame part 14 and has a threaded opposite end 62, which is disposed substantially beyond the end 15 of the frame, which is adjustably engaged by a nut 63. A ratchet wheel 64, all teeth of which face in the same direction is turnably mounted on the unthreaded portion of the shaft 52 between the frame end 15 and nut 63 and an expansion spring 65 is disposed on the shaft 52 between the frame end 15 and the ratchet wheel 64. A large disk

66 having a knurled periphery is mounted on the shaft 52 between the nut 63 and a ratchet wheel 64 and a stronger expansion coiled spring 67 is mounted on the shaft 52 between the ratchet wheel 64 and disk 66. A friction washer 68 is mounted on the shaft 52 between the disk 66 and nut 63. It will be apparent that the nut 63 may be adjusted on the shaft end 62 for varying the tension on the springs 65 and 67. The disk 66 is likewise turnably mounted on the shaft 52 and has a portion of its periphery extending through a transverse slot 69 of the cover plate 58.

An extension 70 of the free end of the bimetallic member 20 extends through a notch or recess 71 in the front portion 15 of the frame 11, below the ratchet wheel 64 and has a pawl 72 secured thereto by a fastening 73 and which extends upwardly and at an oblique angle to engage the shoulders of the teeth of the ratchet wheel 64 which face counterclockwise. A holding pawl 74 is mounted pivotally on a pin 75 which projects outwardly from the frame portion 15 and is yieldably urged into engagement with the teeth of the ratchet wheel 64 by a spring 76 to prevent said ratchet wheel 64 from turning counterclockwise, as seen in Figure 4.

Referring to Figure 7, a positive electrical conductor 77 leads from a source of current supply to an electrical device or devices to be controlled by the switch 10 and energized by the current supply and a negative conductor 78 is likewise connected to the current supply and to the device or devices to be energized thereby. However, the negative conductor 78 is provided with a break, one end of which is connected at 79 to the resilient conductor strip 47 and the other end of which is connected at 80 to the resilient conductor strip 46 so that the circuit from the current supply to the control device or devices will be interrupted when the contact point 48 is out of engagement with the contact point 49. A resistance wire and branch conductor 81 leads from the positive conductor 77 and includes a portion forming a resistance wire which is wound about the bimetallic strip 20. The opposite end of the conductor 81 is connected to the resilient conductor strip 21. Another branch conductor 82 extends between the conductor 78 and the resilient conductor strip 22.

Assuming that the switch parts are in the positions as illustrated in Figure 1, in which positions the circuit as illustrated in Figure 7 will be broken due to the fact that the contact point 48 is out of engagement with the contact point 49, if it is desired to set the switch 10 so that the devices controlled thereby will be energized for a prescribed period, as for example thirty hours, the disk 66 is turned manually in a direction to turn the shaft 52 counterclockwise as seen in Figure 4. The two springs 65 and 67 between which the ratchet wheel 64 is gripped afford a less secure frictional engagement than the spring 67 and friction washer 68 between which the disk 66 is gripped so that shaft 52 will be turned with the disk 66 and relatively to the ratchet wheel 64. This counterclockwise turning movement of the shaft 52 due to the right hand thread of its portion 53 will cause the nut 54 and plate 55, carried thereby, to be displaced from right to left of Figures 1, 2 and 3 since the arm 56 will prevent the nut from revolving with the threaded portion 53. The outer surface of the cover plate 58 may be graduated and calibrated in hours as indicated at 83 in Figure 2 along a side edge of its slot 57 so that the arm

56 can function with said graduations as a pointer for visually indicating when the switch has been properly set to interrupt the circuit after the prescribed time. In this case, the disk 66 would be turned until the arm 56 moved to a position in alignment with the graduation mark "30." As the nut 54 commences its movement from right to left, a portion of the plate 55 will contact the cam surface 43 to turn the cam 41 on its pivot 39 in a counterclockwise direction as seen in Figure 3 to thereby move the surface 44 of the cam into engagement with the spring strip 46 and as said surface is disposed more remote to the pivot 39 than the surface 45, the spring strip 46 will be displaced downwardly, as seen in Figures 3 and 6 so that when the surface 44 is engaging flush against the spring strip 46 the contacts 48 and 49 will be in electrical engagement for closing the electric circuit. Assuming that the nut 54 and plate 55 have been moved to the left so that the arm 56 is in alignment with the "30 hour" graduation, as the circuit to the controlled device or devices has thus been closed by the contacts 48 and 49, such devices, not shown, will be energized and the resistance wire 81 will likewise be energized to heat the bimetallic element 20 due to the fact that the secondary circuit comprising the conductor 81, conductor strip 21, contact points 28 and 29, conductor strip 22 and conductor 82 is likewise closed since the contact points 28 and 29 are in engagement, as seen in Figure 7. As the bimetallic strip 20 is heated it will flex downwardly as seen in Figure 7, or upwardly as seen in Figure 5 or from left to right as seen in Figure 4 and after a partial movement will contact the head 35 so as to displace the pin 34 and resilient strip 23 upwardly as seen in Figure 5. When this occurs, the end of the spring 30 which engages the strip 23 will be moved across the plane of the strip 22 and when this happens, the spring 30 by a snap action will bias the free end of the strip 22 away from the strip 21 to disengage the contact 29 from the contact 28 to thus de-energize the secondary circuit of the resistance wire 81. During this movement of the bimetallic member 20 from left to right of Figure 4 while the resistance wire 81 is energized, its extension 70 and the pawl 72 carried thereby will move to the right as seen in Figure 4 a distance greater than the space between a tooth of the ratchet wheel 64 and less than the space between two of the teeth and as the ratchet wheel 64 is prevented from turning counterclockwise by the holding pawl 74, the pawl 72 will thus be moved relatively to the ratchet wheel to engage the tooth to the right of the tooth which is previously engaged. When the contact 29 is disengaged from the contact point 28 the resistance wire 81 is de-energized and as the bimetallic element 20 cools it swings to the left as seen in Figure 4 and in so moving turns the ratchet wheel 64 clockwise therewith a distance equal to the space between adjacent teeth of said ratchet wheel. Likewise, after a certain travel of the bimetallic element 20 from right to left of Figure 4 its extension 70 will strike the spacing sleeve 36 and move said spacing sleeve to the left as seen in Figure 4 and downwardly as seen in Figure 5 which will cause the strip 23 to be moved toward the strip 22 and in so moving, the end of the spring 30 carried thereby will move back across the plane of the strip 22. When this occurs, the spring 30 by a snap ac-

tion will displace the strip 22 toward the strip 21 and return the contact 29 into engagement with the contact 28 to re-energize the resistance wire 81 so that the operation just previously described will be repeated. Each time that the ratchet wheel 64 is thus turned clockwise as seen in Figure 4 by the pawl 72, as previously described, it will turn the shaft 52 in the same direction due to the frictional coupling provided between the ratchet wheel 64 and shaft 52 by the springs 65 and 67. This will cause the nut 54 and plate 55 to be displaced from left to right of Figures 1 to 3 and 6. As the nut 54 approaches the frame part 15, the plate 55 will pass the surface 43 and move into contact with the surface 42 of cam 41 to rock the cam on its pivot 39 in a clockwise direction as seen in Figure 6 and with the point 84 of the cam fulcruming on the spring strip 46. When this point 84 fulcrums and slides past a dead center position of the pivot 39 and surface 42, the resiliency of the strip 46 will cause the cam 41 to turn rapidly in a clockwise direction so that the strip 46 may spring away from the strip 47 and into engagement with the surface 45, as illustrated in Figure 3, thus allowing the contact point 48 thereof to move out of engagement with the contact point 49 and thereby interrupt the circuit to the device or devices energized by the current supply or source.

A number of sets of blocks 18, strips 46 and 47, bars 37 and cams 41 may be utilized, with the cams 41 spaced longitudinally of one another so that the plate 55 in moving from left to right of Figures 3 and 6 may successively de-energize a number of electrical devices connected to the current supply at different intervals, the last circuit thus being interrupted being the one associated with the secondary circuit of the resistance wire 82. This will be readily accomplished since the plate 55 may continue to turn the cams 41 initially engaged thereby until the cam surface 85 is disposed to contact the strip 46 thereby allowing the plate 55 to clear the abutment surface or shoulder 42 of said cams.

It is not essential that the disk 66 be frictionally coupled to the shaft 52 as said disk could be fixed thereto; however, by the use of the frictional coupling as described, any danger of damage of the parts by turning the disk 66 to too great an extent is eliminated since when the arm 56 engages the left hand end of the slot 57 a further turning of the disk 66 will merely cause it to slip and turn relatively to the shaft 52.

By adjusting the screw 25 the free end of the conductor strip 22 may be displaced toward or away from the strip 23 to vary the extent of travel of the bimetallic element 20 before the secondary circuit 81, 82 will be energized or de-energized and, accordingly, the time interval of the secondary switch 28, 29.

Various modifications and changes are contemplated and may obviously be resorted to, without departing from the spirit or scope of the invention as hereinafter defined by the appended claims.

I claim as my invention:

1. A variable electrically actuated time switch comprising a supporting structure, a shaft journaled in said supporting structure having a threaded portion, a member engaging said threaded shaft portion and slidably connected to the frame structure to traverse the threaded shaft portion when the shaft is revolved; a

ratchet wheel connected to the shaft, a holding pawl to prevent rotation of the ratchet wheel in one direction, a bimetallic element supported at one of its ends by the supporting structure, a pawl on the free end of said bimetallic element engaging the ratchet wheel, a resistance wire adapted to be interposed in an electric circuit to be controlled by the time switch for heating the bimetallic element to move its pawl in one direction relatively to the ratchet wheel, a snap action switch interposed in the circuit of the resistance wire including a part engaged by the bimetallic element to interrupt the circuit of the resistance wire when the bimetallic element is heated and moved to a predetermined extent, said bimetallic element and its pawl being displaced in the opposite direction by the cooling of the bimetallic element to cause the pawl to turn the ratchet wheel and shaft in the last mentioned direction and relatively to the holding pawl, said snap action switch having a part engaged by the bimetallic element when the bimetallic element is moved in the last mentioned direction for returning the snap switch to a circuit closing position to re-energize the resistance wire, a second switch supported by the time switch supporting structure including a resilient contact strip normally spring biased to a circuit interrupting position, said second switch including a pivotally mounted cam having a surface to engage said spring contact strip for maintaining it in a circuit closing position, and said cam having an abutment surface disposed in the path of movement of the member which engages and traverses the threaded shaft portion whereby said member upon reaching a predetermined point in its travel along the threaded shaft portion will engage the abutment surface to turn the cam on its pivot to move said strip engaging surface thereof out of contact with said resilient contact strip to permit said strip to be biased by its resiliency to a circuit interrupting position to break the circuit in which the time switch is interposed.

2. A time switch as in claim 1, said ratchet wheel being frictionally coupled to the shaft, and a knob adapted to be manually actuated and connected to said shaft for turning the shaft in the opposite direction for displacing the member which engages the threaded shaft portion in the opposite direction to the direction in which it is moved by actuation of the ratchet wheel and by the pawl carried by the bimetallic member to reset the switch and to turn the cam in the opposite direction to move said resilient contact strip back to a circuit closing position.

3. A time switch as in claim 1, said ratchet wheel being frictionally coupled to the shaft, and a knob adapted to be manually actuated and connected to said shaft for turning the shaft in the opposite direction for displacing the member which engages the threaded shaft portion in the opposite direction to the direction in which it is moved by actuation of the ratchet wheel and by the pawl carried by the bimetallic member to reset the switch and to turn the cam in the opposite direction to move said resilient contact strip back to a circuit closing position, said knob being frictionally coupled to the shaft by a more positive frictional coupling means whereby the ratchet wheel may be turned more readily relatively to the shaft than said knob.

4. A time switch as in claim 1, said ratchet wheel being frictionally coupled to the shaft, and a knob adapted to be manually actuated

and connected to said shaft for turning the shaft in the opposite direction for displacing the member which engages the threaded shaft portion in the opposite direction to the direction in which it is moved by actuation of the ratchet wheel and by the pawl carried by the bimetallic member to reset the switch and to turn the cam in the opposite direction to move said resilient contact strip back to a circuit closing position, said knob being frictionally coupled to the shaft by a more positive frictional coupling means whereby the ratchet wheel may be turned more readily relatively to the shaft than said knob, said coupling means of the ratchet wheel and knob including expansion springs mounted on the shaft between the ratchet wheel and a part of the supporting structure and between the ratchet wheel and one side of said knob, and a friction washer frictionally engaging the opposite side of said knob.

5. A time switch as in claim 1, said snap switch including a resilient contact blade, a spring strip actuated by swinging movement of said bimetallic member and moved thereby toward and away from said resilient contact blade, a bowed spring having one end connected to the resilient contact blade and its opposite end connected to said spring strip, said last mentioned end being movable with the spring strip, when actuated by the bimetallic element back and forth across the plane of the resilient contact blade for moving the blade by a snap action to a circuit closing or circuit interrupting position for energizing and de-energizing the resistance wire.

6. A variable electrically actuated electric circuit controlling switch comprising a supporting structure, a shaft journaled therein and provided with a threaded portion, a nut engaging the threaded portion and slidably connected to the supporting structure for movement longitudinally of the shaft when the shaft is revolved, a ratchet wheel connected to the shaft, a holding pawl to prevent rotation of the ratchet wheel in one direction, a bimetallic element connected to said supporting structure, an actuating pawl secured to a free end of said bimetallic element and engaging the ratchet wheel teeth, a secondary circuit adapted to be connected to an electric circuit controlled by the time switch including a resistance wire for heating the bimetallic element, a snap switch interposed in the circuit of the resistance wire and actuated by the movement of the bimetallic element for intermittently energizing and de-energizing the resistance wire, said actuating pawl being oscillated by the bimetallic element for movement in one direction relatively to the ratchet wheel and for moving the ratchet wheel with the actuating pawl when said pawl is moved in the opposite direction, a normally open switch controlling the first mentioned circuit including a spring contact normally biased to a circuit interrupting position, said normally open switch being supported by said supporting structure, a swingably mounted cam member having a surface to engage the spring contact to maintain it in a circuit closing position, said cam being disposed in the path of travel of the nut when the shaft is turned by the ratchet wheel to cause the cam to be engaged and rocked by the nut to a position to release the spring contact to permit it to move to a circuit interrupting position.

ROBERT P. MOHN.
